(57) **CLAIM**

The ornamental design for a cable clip for organizing and routing cables and wires, as shown and described.

DESCRIPTION

FIG. 1 is an upper perspective view of a cable clip for organizing and routing cables and wires in accordance with the invention;

FIG. 2 is a front view of the cable clip for organizing and routing cables and wires;

FIG. 3 is a rear view of the cable clip for organizing and routing cables and wires;

FIG. 4 is a left-side view of the cable clip for organizing and routing cables and wires;

FIG. 5 is a right-side view of the cable clip for organizing and routing cables and wires;

FIG. 6 is a top view of the cable clip for organizing and routing cables and wires;

FIG. 7 is a bottom view of the cable clip for organizing and routing cables and wires; and,

FIG. 8 is a cross-section view along line 8 in FIG. 6 of the cable clip for organizing and routing cables and wires.

The broken lines in the drawings represent unclaimed environmental subject matter.
